UNITED STATES PATENT OFFICE.

JOSEPH W. SCHLOSS, OF NEW YORK, N. Y., ASSIGNOR TO CASTLEBONE COMPANY, A CORPORATION OF NEW YORK.

GIRDLE.

1,130,202.

Specification of Letters Patent.

Patented Mar. 2, 1915.

Application filed October 7, 1914. Serial No. 865,445.

To all whom it may concern:

Be it known that I, JOSEPH W. SCHLOSS, a citizen of the United States, residing at the city of New York, in the borough of 5 Manhattan and State of New York, have invented certain new and useful Improvements in Girdles, of which the following is a full, clear, and exact description.

This invention relates to belts or girdles 10 and has special reference to a form or foundation which is intended to support the ornamental fabric of the girdle and maintain it in shape.

The object of the invention is to provide 15 such a foundation which shall be efficient for the purpose intended, durable and cheap to manufacture.

The invention consists of an article constructed as hereinafter described and illustrated.

In the accompanying drawing: Figure 1 is a face view of the girdle foundation when laid open straight and flat; Fig. 2 are views of fractional portions of the edge of the 25 device showing two different styles of fluting or plaiting.

The foundation consists essentially of a straight band 1 of woven fabric, the material of which the band is made being of the 30 nature of buckram, crinoline, haircloth or other comparatively stiff fabric. This band, preferably throughout its length, is fluted, corrugated or plaited as indicated at 2 in Fig. 2, the nature of the material being such 35 that this fluting or plaiting retains its shape indefinitely and the flutings or plaitings are arranged transversely to the length of the band, so that when tension is applied to the extremities of the band, it will yield to the 40 extent afforded by the opening or stretching out of the fluting. For convenience the fluting, plaiting, corrugation or other similar formation which is imparted to the band, will be referred to merely as fluting with 45 the understanding that this term has a scope sufficient to include all of the others. Attached to one face of the band 1 is an elastic tape 3 arranged longitudinally thereof, the particular location being substantially at 50 the waist line when the belt is applied to the body and ordinarily at some intermediate point between the upper and lower edges of the band 1. This elastic tape preferably 55 consists of the usual fabric having rubber strands incorporated therein. It is fixed to

the face of the band 1 in such a manner that its extension and contraction, as well as the extension and contraction of the band itself, are not interfered with. This is accomplished by using a zig-zag stitching 4, such, for instance, as the "herring bone" stitch or a modification thereof. The tape is also preferably secured to the band while the former is under slight tension so that there will be an additional tendency to restore the flutings to their original shape after the band has been distended. Stiffeners such as whale bone or steels may be inserted at intervals as indicated at 5 to maintain the shape of the band, but these are not features of my 70 invention.

The foundation thus described is intended to receive and support an ornamental covering, such as silk or other fabric, which is supposed to be applied thereto with sufficient 75 fullness to permit of limited extension of the foundation when it is applied to the body. The girdle is of course worn around the waist line and assumes and maintains the shape of the body at that location. The 80 function of the flutings is to yield or open and contract locally to accommodate the shape of the human figure without binding around the entire circumference of the body. An elastic band, for instance, would yield 85 locally to enlargements of the body, but it would also be put under strain around the entire body or throughout the length of the elastic portion, whereas, the flutings merely open locally to accommodate an enlargement 90 without drawing on the other portions of the band. The elastic tape 3 will preferably be slightly shorter than the waist measurement of the person who will wear the girdle. This will cause the girdle to fit closely at 95 the waist line and when the girdle is removed from the body, the tape will serve to restore the flutings to their original shape and thus make the article more durable.

I am aware that these girdle foundations 100 have heretofore been made of stiff but flat material cut on the bias so as to yield in a longitudinal direction and fit the shape of the body, but this construction is objectionable because there is practically no limit to 105 the amount of "stretch" which is afforded by material cut on the bias and eventually such a band becomes almost a string. It is not self-restoring to shape and is less durable than the construction herein described. 110

The zig-zag stitching herein referred to may consist of single stitches arranged diagonally to each other as shown or each of the diagonal runs may be composed of a number of stitches, the function being to permit adjacent apexes of the stitching to separate and contract with the fabric.

I claim:

1. A girdle foundation comprising a band 10 of stiff fabric fluted transversely of its length and having an elastic tape secured longitudinally thereto.
2. A girdle foundation comprising a band 15 of stiff fabric fluted transversely of its length and having an elastic tape secured longitudinally thereto intermediate of its upper and lower edges.
3. A girdle foundation comprising a band

of stiff fabric fluted transversely of its length and having an elastic tape secured 20 longitudinally thereto intermediate of its upper and lower edges, said tape being secured under tension to the fabric.

4. A girdle foundation comprising a band 25 of stiff fabric fluted transversely of its length, an elastic tape applied to the face of the band in a longitudinal direction and zig-zag stitching securing the tape to the band for the purpose set forth.

In witness whereof, I subscribe my signature, in the presence of two witnesses.

JOSEPH W. SCHLOSS.
